UNITED STATES PATENT OFFICE.

GUSTAVE F. DANIELSON, OF YOUNGSTOWN, OHIO.

PROCESS OF MAKING SEATS.

1,116,875.

Specification of Letters Patent. Patented Nov. 10, 1914.

Application filed March 9, 1914. Serial No. 823,637.

To all whom it may concern:

Be it known that I, GUSTAVE F. DANIELSON, a citizen of the United States of America, residing at Youngstown, in the county 5 of Mahoning and State of Ohio, have invented certain new and useful Improvements in Processes of Making Seats, of which the following is a specification, reference being had therein to the accompanying drawings.

10 This invention relates to seats for agricultural field machinery and the like, and more particularly to those formed of sheet metal or like metals, and to a method of manufacture whereby a portion of the seat is embossed with a design, trade name or the like and is then molded with the rest of the sheet to the proper conformation without distorting the design already embossed thereon.

15 The invention consists in the matter hereinafter set forth and pointed out in the appended claims.

20 In the drawings, Figure 1 is a plan view of a seat blank for forming a seat that embodies features of the invention; Fig. 2 is a 25 cross sectional view of dies for embossing a design or name on a seat; Fig. 3 is a plan of an embossed seat; Fig. 4 is a cross sectional view of dies for completing the form 30 of the seat, and Fig. 5 is a plan of a completed seat.

25 It is difficult to emboss or press up a design, figures, letters or the like on sheet metal after the latter has been bent from a plain sheet by pressure in dies, without distorting the piece and it can only be accomplished successfully by expensive compound dies. The method herein described consists first, in cutting a blank from sheet metal 35 and stamping thereon a design, letters, figures or the like, while it is still unformed, and then in molding the blank to the desired 40 contour without disturbing or replacing the original design.

45 As herein described a blank 1 is cut out from a sheet metal blank and is given the desired outline thereby. A portion of the seat, indicated at 2, is then operated upon by embossing dies 3 and 4 which strike up characters, figures or any preferred design thereon; 50 thereafter the blank is subjected to drawing or forming dies 5, 6 and 7, which mold it into the contour of the desired completed article without deformation or defacing the portion that is already embossed. An article 55 manufactured in this way presents the same

appearance as an article which has been first formed and then embossed as in the usual method, and may be manufactured at far less expense and difficulty. When cutting the blank 1 from sheet metal, the blank can be 60 provided with the ordinary drain openings 8 or this punching operation can be accomplished at the same time that the dies 3 and 4 are employed for embossing the rim or 65 edge of the seat.

70 By reference to Fig. 4, it will be observed that the die 5 is recessed to provide clearance for the characters, figures or design embossed upon the rim or edge of the seat, and that the die 5 cooperates with the die 6 in holding the rim or edge of the seat while the die 7 completes the formation of the seat, thereby preventing the rim or edge of the seat from being distorted while the blank is 75 being drawn to proper form.

75 By using a convex lower embossing die, as shown in Fig. 2, scales and other foreign matter are prevented from accumulating upon the die and interfering with the proper formation of the characters or design and in 80 consequence of this method of manufacture, the seat can be expeditiously and economically produced.

What I claim is:

1. A process for manufacturing seats for 85 agricultural field machinery which consists in cutting a blank from a plain metal plate, in simultaneously bending and embossing a portion of the blank without otherwise deforming it, and in drawing the central portion 90 of the embossed blank to form without affecting the bent and embossed portion thereof.

2. A process of manufacturing seats for 95 agricultural field machinery consisting in first cutting a blank from a plain metal plate, pressing the edges of the blank between dies to emboss and provide a convex edge for the greater part of the periphery of said blank, and holding the formed edge of 100 the blank between dies while the remainder of the blank is drawn by a die to provide the blank with a concave portion.

In testimony whereof I affix my signature in presence of two witnesses.

GUSTAVE F. DANIELSON.
